Primary Examiner — Mark Goodwin(74) *Attorney, Agent, or Firm* — Wolf, Greenfield & Sacks, P.C.(57) **CLAIM**

The ornamental design for a shovel, as shown and described.

DESCRIPTION

FIG. 1 is a top, front, right side perspective view of a shovel of this invention;

FIG. 2 is a top plan view of the shovel shown in FIG. 1;

FIG. 3 is a bottom plan view of the shovel shown in FIG. 1;

FIG. 4 is a left side elevational view of the shovel shown in FIG. 1;

FIG. 5 is a ride side elevational view of the shovel shown in FIG. 1;

FIG. 6 is a front elevational view of the shovel shown in FIG. 1; and,

FIG. 7 is a rear elevational view of the shovel shown in FIG. 1.

The dashed, broken lines shown in the figures illustrate portions of the shovel that form no part of the claimed design.

1 Claim, 6 Drawing Sheets(56)
